CLAIM

The ornamental design for a storage container, as shown and described.

DESCRIPTION

FIG. 1 is a perspective view of a storage container.
FIG. 2 is a front elevational view of the storage container of FIG. 1.
FIG. 3 is a back elevational view of the storage container of FIG. 1.
FIG. 4 is a side elevational view of the storage container of FIG. 1.
FIG. 5 is a side elevational view of the storage container of FIG. 1 from the opposite side from FIG. 4.
FIG. 6 is a bottom plan view of the storage container of FIG. 1.
FIG. 7 is a top plan view of the storage container of FIG. 1; and,
FIG. 8 is a perspective view of the storage container of FIG. 1 sitting within the ceiling of a semi-truck cab.
The broken lines disclosed in FIG. 8 illustrate environment and form no part of the claimed design.
